US00D710732S

(12) **United States Design Patent**
Calvani

(10) **Patent No.:** **US D710,732 S**
(45) **Date of Patent:** **** Aug. 12, 2014**

(54) **WATCH DIAL**

(71) Applicant: **Maria Cristina Calvani**, Cologny (CH)

(72) Inventor: **Maria Cristina Calvani**, Cologny (CH)

(73) Assignee: **Rolex Watch U.S.A., Inc.**, New York,
NY (US)

(**) Term: **14 Years**

(21) Appl. No.: **29/452,924**

(22) Filed: **Apr. 23, 2013**

(51) LOC (10) Cl. **10-07**

(52) U.S. Cl.

USPC **D10/126**

(58) **Field of Classification Search**

USPC D10/30-39, 122-126, 6, 22, 23;
368/223, 228, 232, 80

See application file for complete search history.
